UNITED STATES PATENT OFFICE.

GILBERT L. CROWELL, JR., OF ARLINGTON, NEW JERSEY, ASSIGNOR TO
DOMINICK & HIAFF, OF NEW YORK, N. Y.

DESIGN FOR A SPOON.

SPECIFICATION forming part of Design No. 21,265, dated December 29, 1891.

Application filed December 1, 1891. Serial No. 413,733. Term of patent 7 years.

To all whom it may concern:

Be it known that I, GILBERT L. CROWELL, Jr., a citizen of the United States, and a resident of Arlington, in the county of Hudson and State of New Jersey, have invented and produced a new, original, and useful Design for Spoons, of which the following is a description, reference being made to the accompanying drawings, which fully illustrate the design as applied to a spoon and are made a part of the following specification.

The general outline of the handle is of a recurring wavy nature, the handle being broadest at the middle top, where it is partially oval in outline. The bowl is of common form in outline.

Referring now to Figure 1, which represents the front of the spoon, the leading features of surface ornamentation are as follows: At the top of the spoon is represented a cross A, of ecclesiastical form and design, at the sides of and below which are Romanesque leaves. B is the representation, in portrait style, of the head and shoulders of a man, the garb being of a pontifical character and the portrait being surrounded by a bead-like border. The shank has a raised-border edge C and bears at the

top beneath the portrait B indicating characters in ornamental form and arrangement, and along the narrow part of the shank is 30 represented a rosary D. The front or concavity of the bowl bears the representation of a plaza E and a cathedral-like building F, with other buildings on either side thereof.

Fig. 2 shows the back of the spoon. This 35 back bears a raised and partly-ornamental border G, the uppermost portion of the handle and the surface of the shank being otherwise plain. At the top of the back is represented a tiara H, beneath which is a coat of 40 arms I. The top of the back of the bowl bears an inverted cross J in the form and style of a decoration.

What is claimed as new is—

1. The design for spoons, substantially as 45 herein shown and described.
2. In the design for a spoon as herein shown and described, the front thereof.
3. In the design for a spoon as herein shown and described, the back thereof.

GILBERT L. CROWELL, JR.
